SPRING DIVING APPARATUS

Henry J. Lehfeldt, 4631 SW. 5th Terrace, Miami 44, Fla., and Arthur O. Lehfeldt, 62 Miracle Mile, Coral Cables, Fla.

Filed July 13, 1959, Ser. No. 826,540

11 Claims. (Cl. 272—66)

This invention relates to apparatus for use with diving boards and platforms for the purpose of applying an impulse or thrust to the board in addition to that imparted by its natural resiliency.

It is the principal purpose of the invention to provide a diving board or platform powered by resilient means such as a spring.

Another object is to provide a diving board in which energy in the resilient means such as a spring, is controlled by the diver and released in response to a predetermined number of oscillations imparted to the board, or to a preselected stress of the resilient means.

A further object is to provide an apparatus of the type aforesaid which may be readily applied to existing diving boards or platforms with little or no alterations, or incorporated as an integral feature of new boards.

Still another object is to provide a diving apparatus of the kind mentioned which is relatively simple and inexpensive to construct, positive and reliable in operation and easily serviced and repaired.

Yet another object is to provide a diving apparatus which adds greatly to the thrill of diving and which is a valuable aid to instructors of swimming and diving.

Other objects and advantages of our invention will be apparent to those skilled in the art after a study of the following description in connection with the accompanying drawing.

In the drawing:

Figure 1 is a view to a reduced scale showing the general locale of the invention applied to an existing diving board;

Figure 2 is a side elevation, partly in section, showing one of the spring-powered units forming a part of our invention;

Figure 3 is a perspective view to about the same scale as Figure 2, showing the mechanism by which the stored energy in the spring or other power means, is released, and its manner of adjustment;

Figure 4 is a plan view of a portion of a diving board or platform and showing the manual adjustment and indicator, by which the thrust of the spring or springs at release, is controlled and indicated;

Figure 5 is a sectional view to a scale enlarged over that of Figure 2, of the means by which the return of the rack member to operating position, is delayed momentarily following release; and

Figure 6 is a perspective view to a somewhat reduced scale, showing the rack member.

Referring in detail to the drawing wherein like reference numerals identify corresponding parts throughout, 1 indicates a spring-powered unit which, from Figure 1 is seen to be mounted beneath a diving board B so as to be responsive to the downward movement thereof as a diver causes the board to oscillate. As shown, the apparatus is contained within a casing 2 of plywood or metal, such as aluminum.

A heavy collar 3 is secured to the bottom 2b of the casing, as by cap screws or bolts 4, and has a central

2

threaded aperture 5 within which is threaded a heavy metal cylinder 6. The cylinder is closed at its top by a cap 7 and contains a plunger 8 loosely fitting the same, for vertical guided reciprocation therein. A plunger rod 9 has one end attached to plunger 8 as by threads and lock nut 10, and extends upwardly through a central guide hole in cap 7. A heavy coil spring 11 is positioned within the cylinder 6, to be compressed by downward movement of the plunger.

At a suitable distance above plunger 8, rod 9 has a holding pawl 12. In Figures 2 and 3 this pawl is shown as rigidly fixed, as by welding, to rod 9. However, to facilitate installation and adaptation to existing boards, it is contemplated that this pawl may be adjustably fixed to the rod, as by threads and lock nuts, set screws, or in any other known way. It is also contemplated that the lower part of rod 9, that is, the portion traversing through cap 7, may be of square or other non-circular section, with a correspondingly-shaped aperture in cap 7, so that the rod will be prevented from turning without direct attachment to the diving board.

Above pawl 12 the rod 9 is provided with a rack 13 shown as cut therein. A slide 14 has a guide hole through which the rod passes with a smooth fit. This slide includes a pair of laterally-extending integral lugs 15 which have aligned bearings journaling a shaft 16. A pinion 17 is fixed to shaft 16 and extends through a slot, not shown, in the wall of slide 14 between lugs 15 and into mesh with rack 13. A release pawl 14a projects integrally from slide 14 and is so disposed that it eventually engages the end of a rack 40, subsequently described, to cam the rack to release position.

Slide 14 has a second bore offset from and parallel with that through which rod 9 passes. This second bore houses 35 a worm, not shown, journaled therein on a vertical axis and in mesh with a worm gear 18, Figure 3, also fixed to shaft 16. A flexible shaft or Bowden cable 19 extends from the top of housing 14, as clearly shown upon Figure 3, to an indicator mechanism generally identified at 20, shown upon Figure 4 as attached to the side of board B near the anchored end thereof. Also from this figure it will be noted that we have shown two of these spring units 1 and 1a, mounted in side-by-side relation beneath the board. Thus, shaft 16 extends transversely from unit 1 to unit 1a, where it is connected with pinion 17 thereof. In unit 1a, of course, worm gear 18 may be omitted, as well as cable 19. The arrangement thus provided enables simultaneous and equal vertical adjustment of the slides 14 of units 1 and 1a, from a single drive 19.

The indicator 20 may comprise a flat housing 21 having a vertical dimension not greater than the thickness of board B and attached to one side edge thereof by screws 22. The housing contains a gear 23 journaled therein and having a portion viewable through an opening 24 in cover 25 secured in position by machine screws 26. The gear 23 has secured to its upper face a plate or dial bearing graduations of effective spring force at release and/or the number of oscillations of the board to effect release thereof. These graduations may be read against an indicator 27, which may be fixed to a transparent pane, not shown, secured in water-tight relation with cover 25 over opening 24. A pinion 28 meshes with gear 23 within housing 21. This pinion is fixed to a shaft which extends vertically through a bushing, not shown, in cover 25. A handle 29 is fixed to the top end of the shaft. The lower end of the shaft is connected or coupled with the core of flexible shaft 19. In this manner, turning of handle 29 operates to vertically adjust the slides 14 of units 1 and 1a and at the same time effects proportional turning of indicator gear 23 to give an indication of the spring force at release and/or the number of

jumps or oscillations of the board necessary to effect release.

As shown upon Figure 2, a clevis 30 is fixed to the top of shaft 9 to receive a lug 31 secured to the under side of board B. A pivot pin 32 connects the clevis and lug so that the shaft 9 is moved vertically in response to oscillations of the board.

Cylinder 6 has a split collar 33 clamped about its lower end as by means of a bolt 34. This collar has diametrically opposite aligned trunnions one of which is identified at 35, Figure 2. A rack member generally identified at 36 and shown in perspective at Figure 6, comprises an inverted U 37 the lower ends of which are forwardly offset and provided with aligned bearing holes 39 to receive the respective trunnions 35. A rack 40 rises vertically from the central portion of the U and is formed with a number of teeth 41 in cooperative relation with holding pawl 12, as will be clear from inspection of Figure 2. In this way, shaft 9 is held in successively lower positions.

Rack member 36 is urged into engagement with pawl 12 about the axis of aligned trunnions 35, by a combined spring and dashpot element 42, Figures 2 and 5. This element is supported from a bracket 43 shown as fixed to one side wall of container 2 as by screws 44. The dashpot cylinder 45 has one end threaded to affix cap 46. A piston 47 has a smooth pressure-tight fit within the cylinder and its rod 48 extends through a guide hole in cap 46 and is pivoted by eye 49 to bracket 43. A coil spring 50 is positioned within cylinder 45 between piston 47 and the bottom of the cylinder. The base or closed end of the cylinder has a pin 51 fixed therewith and extending axially into a rounded depression 52 in the back edge of the rack 40. The dashpot device thus acts in a way obvious from inspection of Figures 2 and 5 to urge the rack into engagement with pawl 12.

Cylinder 45 has a slot 53 in its wall, as well as a check valve 54 in its closed end, so disposed as to permit outflow of air between piston 47 and the closed end, but preventing flow into the cylinder. The slot 53 is so dimensioned and located that during play of the cylinder back and forth in response to step-by-step downward movement of pawl 12, the piston does not move over the ends thereof so that, under such conditions there is no damping effect produced. However, when release pawl 14a finally engages the upper end of rack 40, the greater angular movement imparted to the rack, causes cylinder 45 to move to the left, as the parts are viewed upon Figure 5, a distance such that piston 47 is moved beyond the right end of the slot 53, thus trapping a body of air within the cylinder. On further movement of the cylinder to the left, a quantity of air is forced out through check valve 54. Thus at the instant rack 40 is released from pawl 12, the movement of cylinder 45 to the right is momentarily checked due to below-atmospheric pressure in the dashpot. The delay is sufficient to effect the desired release of energy stored in spring 11.

The operation will be clear from the foregoing description and may be briefly resumed as follows: A diver desiring to use the invention turns handle 29 until the desired spring force is indicated on dial 23 opposite pointer 27. At the same time shaft 16 is rotated from flexible shaft 19, to correspondingly vertically adjust slide 14 and the release pawl 14a. The indication may also be in terms of the number of oscillations or jumps necessary to effect release by pawl 14a.

The diver may then jump up and down on the board and with each corresponding oscillation, pawl 12 is moved down one notch on rack 40, spring 11 is further compressed and slide 14 is simultaneously brought that much nearer the end of the rack. When release cam or pawl 14a finally engages the end of rack 40 after the set number of oscillations, rack 40 is cammed thereby out of engagement with pawl 12 and the stored energy in the spring is instantaneously released to impart an

upward thrust to the board in addition to its inherent or natural resiliency. The diver is thereby projected upwardly with added velocity and height, for a thrilling dive. Alternatively, the diver may oscillate the board one less than the set number, then make a running dive.

While we have shown the form of our invention presently preferred by us, various alterations and substitutions are possible and will readily occur to those skilled in the art after a study of the present disclosure. For example, collar 33 may be threaded onto cylinder 6. Pin 51 may be made adjustable in length for a fine accurate adjustment after installation. Also, while we have shown the board B as equipped with two of the spring units 1 and 1a, it is contemplated that one, three or even more of such units may be installed depending upon the extra thrust desired at maximum setting. Of course, where one unit only is used, the extension of shaft 16 is omitted. Or where three or more are used in side-by-side relation, the shaft or an extension thereof, is connected with the third unit as has been described herein for the second. The apparatus may also be used by acrobats and gymnasts for increased exercise, pleasure and thrills.

Therefore, the foregoing disclosure is to be taken in an illustrative rather than a limiting sense; and it is our desire and intention to reserve all modifications within the scope of the subjoined claims. In these claims, the term "board" is to be taken as inclusive of platforms and other supports from which a dive or leap is made. The term "vertical" as used in the claims refers solely to the position of the part thus referred to, as it appears on the drawing and not to any limiting position of use.

Having now fully disclosed our invention, what we claim and desire to secure by Letters Patent is:

1. In a diving apparatus for use with a diving board, compressible resilient means, compressing means operated by and in response to successive, discrete oscillations of the board to store progressively increasing energy in said resilient means, and means responsive to the final one of a preselected number of oscillations of said board, to instantaneously release to the board, energy stored in said resilient means.
2. The combination with a diving board, of a stressible resilient element, means actuated by and in response to successive, discrete oscillations of said board to increasingly stress said resilient element step by step, and means releasing said resilient element in response to a preselected number of oscillations of said board and imparting the energy stored in said resilient element as an upward thrust on said board.
3. In a diving apparatus of the type described, a vertical rod mounted for longitudinal movement by and in response to oscillations of a diving board, rack means coacting with said rod to hold the same in successive positions of longitudinal movement in one direction, spring means increasingly stressed by successive movements of said rod in said one direction, and means responsive to a preselected total movement of said rod to instantaneously release to said rod the total energy stored in said spring means and move the same in the opposite direction.
4. An apparatus for use with a diving board comprising, a frame, a rod, a plunger fixed to one end of said rod, guide means carried by said frame and mounting said rod and plunger for reciprocation, an abutment fixed in said frame, a coil spring interposed between said abutment and plunger to be stressed by movement of said plunger, rack and pawl means carried by said rod and frame and operable to hold said rod in successive positions of increased stress of said spring, and means responsive to a predetermined total movement of said plunger to release the energy stored in said spring as a longitudinal thrust on said rod.
5. In an apparatus of the type described, first means adapted for connection with a diving board, second means moved in one direction step by step by said first means

in response to discrete successive oscillations of said board, a spring stressed by movement of said second means in said one direction, means responsive to a predetermined cumulative movement of said second means to release said spring and the accumulated energy therein, and means applying said energy as a thrust on said board.

6. In an apparatus of the type described, a vertical rod mounted for connection of its upper end with a diving board, a spring urging said rod in longitudinal upward movement, rack and pawl means associated with said rod and support to hold said rod in successively lowered positions against the correspondingly increasing stress of said spring, means yieldingly urging said rack and pawl means into cooperating relation, and means operated in response to a selected total downward movement of said rod to render said rack and pawl means inoperative and effect an instantaneous upward thrust on said rod by the energy released from said spring.

7. In a diving board apparatus, a casing, a cylinder fixed to the base of said casing with its axis vertical, a plunger slidably fitting said cylinder, a coil spring within said cylinder to be stressed by movement of said plunger, a rod fixed with said plunger and extending vertically exteriorly of said casing, a pawl fixed with said rod, a rack member mounted in said casing for movement toward and from said rod, means yieldingly urging said rack member into cooperative relation with said pawl, to hold said rod in successive positions of increasing stress of said spring, and means carried by said rod for adjustment therealong and engageable with said rack to release the same from said pawl.

8. In an apparatus for use with a diving board, a casing, a cylinder positioned vertically in said casing, a centrally apertured cap closing the upper end of said cylinder, a plunger loosely fitting said cylinder for vertical reciprocation therein, a rod fixed with said plunger and extending upwardly through the aperture in said cap for guided movement, a coil spring in said cylinder between the lower end thereof and said plunger, a holding pawl fixed on said rod, a rack mounted in said casing for pivoting about an axis normal to said rod adjacent the base of said cylinder, said rack being generally parallel with the path of said holding pawl, resilient means urging said rack so that its teeth are successively engaged and held by said holding pawl in motion of said rod and plunger to compress said spring, and a release pawl on said rod above said holding pawl, said release pawl operating to engage and cam said rack out of the path of said holding pawl.

9. An apparatus as recited in claim 8, said release pawl being mounted for longitudinal adjustment on and along

said rod, and manually operable means remote from said casing and connected with said release pawl to longitudinally adjust the same on and along said rod.

said rod, and manually operable means remote from said casing and connected with said release pawl to longitudinally adjust the same on and along said rod.

10. In a diving board apparatus, a casing, a rod, means mounting said rod in vertical position in said casing for guided longitudinal reciprocation therein, the upper end of said rod extending exteriorly of said casing, a spring in said casing urging said rod upwardly, a holding pawl fixed on said rod within said casing, a rack member in said casing mounted for movement toward and from said rod, dashpot means yieldingly urging said rack member into cooperating relation with said holding pawl, a slide mounted on said rod above said holding pawl, release means carried by said slide and engageable with said rack member to release the same from said holding pawl, manually operable means connected with said slide to adjust the same on and along said rod, said dashpot means including a cylinder operated by said holding pawl, a piston slidably fitting said cylinder, a rod fixed to said piston and pivoted to said casing, a spring between said piston and the end of said cylinder contiguous said rack member, said release means moving said rack member a greater distance than said holding pawl, there being a slot through the wall of said cylinder longitudinally thereof, the end of said slot toward said rack member being covered by said piston in response to movement of said cylinder by said release means, and a check valve in said cylinder permitting exit only of air therefrom.

11. In an apparatus for use with a diving board, first means engageable with a diving board to be moved by and in response to oscillations thereof, second means associated with said first means to hold the same in a position of cumulative movement proportional to the number of said oscillations, resilient means progressively tensioned directly by successive discrete movements of said first means, and means responsive to a preselected cumulative movement of said first means to render said second means temporarily inoperative and thereby release the energy stored in said resilient means as a thrust upon said first means and the diving board.
